SLIDE LOOP

George Henry Elwell, New Haven, Conn., assignor to Eastern Tool and Manufacturing Company, Bloomfield, N. J., a corporation

Application November 18, 1943, Serial No. 510,751

1 Claim. (Cl. 24—170)

This invention relates to slide loops, the physical combination of a slide, adjustable upon a strap, and a button loop adapted to clip over a button carried by a garment to be thereby supported, the invention more particularly relating to the slide portion of the device.

It is old to provide a pair of strap loops in a common plane and separated by an intermediate bar into which loops two straps together are threaded against accidental sliding movement thereon, but it has required the ingenuity of invention to provide a similar form of slide for a fixed threaded relation thereof with a single strap. Such form, however, has been constructed and reduced to practice but, to obtain a binding effect, one of the pair of loops usually made of wire, is so constructed that the strap passage is marginally reduced to snugly receive the thick marginal hems of the strap thus bound therein.

The invention about to be disclosed resides in such an improvement of a pair of loops structure wherein the binding effect upon a single strap is acquired by means of the peculiar form and association of an intermediate bar to a wire loop structure of a slide loop of which the binding element does not involve the marginal portion of the strap.

With reference to the accompanying drawing, the Figure 1 is an upright front view of the device; Figure 2 is a similar view of the device illustrating a rear view of an openly swung intermediate bar; Figure 3 is a side elevation of the device illustrating a front view of an openly swung intermediate bar and outline of a strap threaded into the device, but with a generous outwardly looped extension thereof to admit the bar to swing therethrough to either closed or fully opened position; Figure 4 is a similar side elevation illustrating in outline a strap snugly engaged within the device; Figure 5 is a fragmentary face view of a strap illustrating the marginal hems in exaggerated perspective; and Figure 6 is a perspective of a detail.

Attention being called more particularly to the accompanying drawing, the numeral 1 designates the upper horizontal bar of the wire structure; 2 and 3 the side bars thereof; 4 and 5 the relative spaced horizontally aligned portions of the lower bar structure, and 6 and 7 the resilient companion arms integrally depending from the said aligned portions to provide a button-receiving loop 8 and a button-retaining loop 9, the wire terminals 10 and 11 being formed to receive a uniting clip (not illustrated), the upper portion of the wire structure providing the rec-

tangular opening 12, which, when divided by an intermediate bar, comprises a pair of loops 12' and 12'' in a common plane. The numeral 20 designates the intermediate bar of sheet-stock, of metal or plastic, having the looped hinged end 21 for a swinging engagement upon one of the sides, 2 or 3, of the wire structure, as at 3, and a clasp 22 adapted to catch upon the opposite side bar, as at 2. The lower edge of the intermediate bar 20, as at 23, is reinforced by means of a folded edge in close proximity to the spaced aligned lower-bar portions 4 and 5, and a central portion of the upper edge of said bar, as at 24, is also reinforced by means of a flange projecting forwardly into the opening 12 during the closed position of the bar 20 and adapted to function as a strap binding element in close offset proximity to the upper horizontal bar 1. The intermediate bar 20, upon either side of the centrally flanged edge 24, is recessed to provide the enlarged openings, as at 25 and 26, to adequately accommodate the marginal thick hems S' of a two-ply single strap S illustrated by the Figure 5, the strap portions being relatively secured, one to the other, by the stitching S'', a central thin portion S4 lying between the hems S'.

For compact shipment, the relatively movable parts of the device are maintained in closed position, as illustrated by the Figure 1. To mount the device upon a single strap, however, the bar 20 is pulled open against the holding propensities of the clasp 22 and swung to a fully open position upon its hinged end 21, as illustrated by the Figure 2. The looped portion S''' of the strap S, as illustrated by the Figure 3, in dotted edge outline, is passed from the rear of the device into the wire rectangular opening 12 a sufficient distance to permit the intermediate bar 20 to pass into and through the loop S''', to its closed position illustrated by the Figures 1 and 4. The looped portion S''', of the strap S is then drawn into the device to the snug dotted position illustrated by the Figure 4. In such drawn-in position, the thick hems S' of the strap S rest without additional bulging within the enlarged openings 25 and 26 and the intermediate thin portion S4 of the strap S engages over the flange 24 of the closed intermediate bar 20 and under the upper horizontal bar 1 of the wire formation, thus binding the strap S within the slide loop against accidental sliding of the device upon the strap S.

To readjust the device longitudinally of the strap following the mounting of the device

thereon, the bar 20 remaining in its closed position, the strap portion S'''', snugly looped over the bar 20, is substantially lifted away from the bar 20 and the binding flange element 24 so that the strap is thereby adapted to be adjusted above and below the bar 20 before being drawn in again over the flange element 24.

While the clasp 22 is provided as a fastening element for the free end of the bar 20, yet the same is unnecessary; for the closed bar 20 is adequately held in position by means of a threaded strap S within the device. The cut-metal edge 22' of the clasp 22 is adapted to be snapped by the side bar 2 as the intermediate bar 20 is swung to closed position, thereby positioning the clasp-loop 22'' to become lockingly engaged partially around the side bar 2. To omit the clasp element might aid in the longitudinal adjustment of the device along the strap in the same manner as that above described.

An advantage of the invention is that, with the improved swinging intermediate bar 20, a closer strap passage just below the upper horizontal bar 1, and just above the horizontally spaced aligned lower bar portions 4 and 5, may be had which, if the bar 20 were held permanently fixed to the wire structure, would provide insufficient space within and through which to thread a strap. The swinging of the bar 20 out of the way of the rectangular opening 42 leaves that entire opening 42 into which to pass the looped strap S'''. It is this closer strap passage above and below the closed intermediate bar 20 that provides the tenacious binding ef-

fect upon a single strap. A further advantage of the invention is that it enables the mounting of the device upon a strap without first inserting an end of the strap into threaded relation to the intermediate bar 20 separating the strap passages; for the improved device may be mounted at the direct location upon the strap where it is desired that it shall remain.

I claim:

- 10 A slide loop including a substantially rectangular wire loop formation having an upper bar, slightly resilient side bars and lower bar portions from which side arms of a button loop integrally depend; a sheet-material intermediate bar of which one extremity is movably carried by one of said side bars and adapted to engage the opposite side bar, said intermediate bar having sufficient width to substantially occupy the interior of the wire looped formation; a flanged projection provided by the upper edge of the intermediate bar and adapted to project outwardly from said rectangular formation; recesses provided by the upper edge of the intermediate bar, one on each side of said flanged projection; and a looped portion of a strap having marginal hem inserted into rectangular formation from the rear thereof, the looped strap portion receiving therethrough the movable bar as it is moved to its closed position, the taut strap being held between said hem by the flanged projection and said upper bar and the marginal hem within said recesses.
